Patented May 10, 1921.

UNITED STATES PATENT OFFICE.

NILS D. LEVIN, OF COLUMBUS, OHIO, ASSIGNOR TO THE JEFFREY MANUFACTURING COMPANY, OF COLUMBUS, OHIO, A CORPORATION OF OHIO.

MINING APPARATUS.

1,377,842.

Specification of Letters Patent. Patented May 10, 1921.

Application filed March 8, 1917, Serial No. 153,471. Renewed April 2, 1921. Serial No. 453,088.

To all whom it may concern:

Be it known that I, NILS D. LEVIN, a citizen of the United States, residing at Columbus, in the county of Franklin and 5 the State of Ohio, have invented certain new and useful Improvements in Mining Apparatus, of which the following is a specification, reference being had therein to the accompanying drawing.

10 The present invention relates to certain new and useful improvements in slack shoveling devices adapted to remove the cuttings produced by the cutter bits of mining machines of the well known short wall 15 types.

In machines of the short wall types the coal is commonly cut by an elongated cutting mechanism adapted to be thrust longitudinally into the material to be mined, at 20 one side of the working face, and afterward moved laterally across the working face to form a kerf beneath the body of the vein to facilitate breaking down the material for transportation from the mine. In such machines the cuttings produced by the cutting mechanism are drawn rearwardly by the movement of the cutting bits and discharged within the main frame of the mining machine as the bits pass around the 25 driving sprocket wheel. The accumulation of cuttings in proximity to the sprocket wheel tends to choke the machine and cause the bits to carry slack forward along the return side of the cutter arm to be dropped 30 in the kerf thereby interfering with the proper breaking down of the material. As heretofore practised these cuttings have been removed by the use of a shovel in the hands of the miner's helper. To meet 35

40 the requirements of modern methods of mining, larger and more powerful mining machines have been developed wherein the cutter arm sometimes projects as much as ten or twelve feet under the coal. In such 45 machines it has been found that the capacity of the machine is often limited by the ability of the helper to shovel away the slack and better means of slack removal are required in order that the proportions of the 50 cutting mechanism may be increased to the limit of economical operation.

It is the especial object of this invention to provide a mechanically actuated shoveling device, for the removal of these cuttings, 55 which may be conveniently attached to the

mining machine when it is in position for operation or may be separated therefrom for transportation from one working place to the next.

The devices by which I accomplish this 60 purpose are set forth in the following specification and illustrated in the accompanying drawings of which—

Figure 1 is a plan view of a short wall mining machine of well known construction 65 equipped with the slack shoveling device of my invention.

Fig. 2 is a side elevation of the devices illustrated in Fig. 1.

Fig. 3 is a cross section along the line 70 3—3 of Fig. 1.

Fig. 4 is a cross section along the line 4—4 of Fig. 1.

Fig. 5 is a rear elevation of my slack shoveling device. 75

Like numerals refer to similar parts in the several figures.

For the purpose of illustration I have shown in the drawings a short wall mining machine of well known construction having 80 a main frame 1 supported upon a base plate 2 which is adapted to rest upon and slide over the floor of the mine. Supported upon the main frame 1 is a horizontally projecting cutter frame 3 about the edges of which 85 travels a cutter chain 4 having renewable cutter bits 5 adapted to engage the material to be mined. The cutter chain 4 passes around a sprocket wheel 6 positioned near the rear end of the machine and connected 90 through suitable gearing, not shown in the drawing, with the motor 7 mounted upon the main frame 1. Power to actuate the motor 7 is supplied from a convenient source of electric supply through the flexible conductor cable 8, and controlling devices 9 are arranged for convenient manipulation by the operator to control the operation of the motor 7. A winding drum 10 is mounted 95 upon the frame 1 of the mining machine and connected through suitable gearing, not shown in the drawing, with the motor 7. A cable 11 is arranged to be wound upon the drum 10 and extend around suitable guide sheaves to an anchor outside of the 100 machine in such manner that by the winding of the cable upon the reel the machine will be moved over the floor of the mine to perform its cutting operations. A second winding drum 12 is mounted upon the main 105 machine 110

frame 1 and upon this drum is windable a cable 13 which after passing around suitable guide sheaves 14 and 15 may be attached to an anchor outside of the machine. Suitable brake mechanism is provided to retard the unwinding of this cable 13 thereby balancing the strain produced by the cutting mechanism and the feed cable to hold the mining machine in proper working relation to the face of the vein.

Positioned immediately in the rear of the mining machine is my improved shoveling device, indicated as an entirety in the drawings by the numeral 16. Coupling links 17 and 18 adapted to engage with suitable apertures in the main frame 1 of the mining machine, afford means for removably connecting the shoveling device with the mining machine. The active element of the shoveling device is an endless chain 19 which passes around the driving sprocket wheel 20 and the idler wheel 21 both of which are mounted for rotation about vertical axes. Secured to the chain 19 at spaced intervals are a plurality of perpendicularly extending flights 22 which serve to engage the coal cuttings and push them into and along an inclined conveyer trough 23 to be discharged in piles at such a distance in the rear of the machine that they will be out of the way of the miner while handling the mining machine or when breaking down and loading the coal. A similar trough 24 is provided for supporting the return strand of the conveyer element. The conveyer troughs 23 and 24 are supported by a self contained structure 25 in the upper member of which is formed the guide ways 26 and 27 along which the chain 19 travels. The lower member of the supporting structure is expanded laterally to form a base plate 28 adapted to rest upon and slide over the floor of the mine. At its forward end the bottom plate 29 of the conveyer trough is arranged to overlap the base plate 28 of the mining machine in close proximity to the sprocket wheel 20 in such manner as to receive the coal cuttings when discharged by the centrifugal action of the cutter bits as they pass around the sprocket wheel. The head sprocket wheel 20 is mounted upon the upper end of a vertical shaft 30 journaled in the bearing 31 of the supporting structure 25. To the lower end of the shaft 30 is attached a bevel gear 32 which engages a similar bevel gear 33 fixed to the transverse driving shaft 34. The shaft 34 is journaled in bearings 35 of the supporting structure and has upon its projecting end a sprocket wheel 36 in alinement with a similar sprocket wheel 37 upon the mining machine to which it may be connected by an endless chain 38. The sprocket wheel 37 is connected with the motor of the mining machine through a train of gears, not shown in the drawing,

thereby affording power for the actuation of the shoveling device.

After the completion of the sumping, or entering, cut, when the mining machine has been adjusted to begin its lateral cutting operation, the shoveling device, as above described, will be placed in position at the rear of the mining machine, the coupling links 17 and 18 engaged with the apertures of the mining machine frame 1, and the driving chain 38 put in place upon the sprocket wheels 36 and 37 to drive the shoveling conveyer. As the mining machine advances along the coal face the cuttings produced by the cutter bits 5 will be discharged by the centrifugal action of the bits passing around the sprocket wheel 6 and will be received by the plate 29 of the shoveling conveyer. From the plate 29 these cuttings will be gathered by the scraper flights 22, and propelled rearwardly and upwardly through the trough 23 and discharged at the rear of the machine at such distance from the coal face that they will not interfere with the manipulation of the mining machine or with the breaking down and loading of the coal. After the completion of the cut across the face of the coal the coupling links 17 and 18 and the driving chain 38 will be disconnected from the mining machine, and the mining machine and shoveling device may be separately transported to the next working place.

What I claim is—

1. In a mining apparatus, the combination with a mining machine adapted to be moved along the face of the coal to form a kerf at the base thereof, a supplemental frame detachably connected to and movable with said mining machine, conveying mechanism mounted upon said supplemental frame adapted to receive the coal cuttings from the mining machine and remove them from proximity therewith.

2. In a mining apparatus, the combination with a mining machine adapted to be moved along the face of the coal to form a kerf at the base thereof, a supplemental frame detachably connected to and movable with said mining machine, conveying mechanism mounted upon said supplemental frame and actuated from the power devices of the mining machine to receive the coal cuttings from the mining machine and remove them from proximity therewith.

3. In a mining apparatus, the combination with a mining machine adapted to be moved along the face of the coal to form a kerf at the base thereof, a supplemental frame adapted to rest upon and slide over the floor of the mine, means to connect said supplemental frame with said mining machine to move it therewith, conveying mechanism mounted in said supplemental frame adapted to receive coal cuttings from said

mining machine and remove them from proximity therewith.

4. In a mining apparatus, the combination with a mining machine comprising a main frame adapted to be moved along the face of the coal and an elongated cutting mechanism carried by said main frame and adapted to form a kerf at the base of the vein, of a supplemental frame adapted to rest upon the floor of the mine and to be detachably connected to and to move with said main frame, and conveying mechanism mounted upon said supplemental frame and adapted to receive the coal cuttings from said cutting mechanism and to remove them from proximity to the mining machine.

5. In a mining apparatus, the combination with a mining machine comprising a main frame adapted to be moved along the face of the coal, an elongated cutting mechanism carried by said main frame and adapted to form a kerf at the base of the vein, and a motor mounted upon said main frame to actuate the operative parts of the mining machine, of a supplemental frame adapted to rest upon the floor of the mine and to be detachably connected to and to move with the said main frame, a conveying mechanism mounted upon the supplemental frame and adapted to receive the coal cuttings from said cutting mechanism and to remove them from proximity to the mining machine, and means to actuate the said conveying mechanism from the motor of the mining machine.

6. In a mining apparatus, the combination with a mining machine having a main frame adapted to movement over the floor of the mine, a sprocket wheel mounted in said main frame, a cutter chain actuated by said sprocket wheel and adapted to travel in a horizontal path to form a kerf at the base of the coal vein, a supplemental frame adapted to rest upon and slide over the floor of the mine, means to connect said supple-

mental frame with said main frame to move it therewith, conveying mechanism mounted upon said supplemental frame and extending to points adjacent said sprocket wheel to receive coal cuttings delivered by said cutter chain and remove them from proximity with the machine.

7. In a mining apparatus, the combination with a mining machine having a main frame adapted to movement over the floor of the mine, a sprocket wheel mounted in said main frame, a cutter chain actuated by said sprocket wheel and adapted to travel in a horizontal path to form a kerf at the base of the coal vein, a supplemental frame detachably connected to and movable with said main frame, conveying mechanism mounted upon said supplemental frame and extending to points adjacent said sprocket wheel to receive coal cuttings delivered by the cutter chain and remove them from proximity with the machine, and means to actuate said conveying mechanism from the power devices of said mining machine.

8. In a mining apparatus, the combination with a mining machine having a main frame adapted to movement over the floor of the mine, a sprocket wheel mounted in said main frame, a cutter chain actuated by said sprocket wheel and adapted to travel in a horizontal path to form a kerf at the base of the coal vein, a supplemental frame detachably connected to and movable with said main frame, conveying mechanism mounted upon said supplemental frame and extending to points adjacent said sprocket wheel to receive the coal cuttings delivered by the cutter chain and remove them from proximity with the machine.

In testimony whereof I affix my signature, in the presence of two witnesses.

NILS D. LEVIN.
